(57) **CLAIM**

The ornamental design for a press-down novelty toy, as shown and described.

DESCRIPTION

FIG. 1 is a perspective view of a press-down novelty toy showing my new design;

FIG. 2 is a front elevational view of the press-down novelty toy shown in FIG. 1;

FIG. 3 is a left side elevational view of the press-down novelty toy shown in FIG. 1;

FIG. 4 is a top plan view of the press-down novelty toy shown in FIG. 1;

FIG. 5 is a right side elevational view of the press-down novelty toy shown in FIG. 1;

FIG. 6 is a back elevational view of the press-down novelty toy shown in FIG. 1; and,

FIG. 7 is a bottom plan view of the press-down novelty toy shown in FIG. 1.

The broken line showing of the battery compartment of a press-down novelty toy is included for the purpose of illustrating environmental structure and forms no part of the claimed design.
